Fig. 2.

A detailed technical drawing of a mechanical assembly. It features a horizontal base with a central slot. A vertical lever, labeled '67', is attached to the left side of the base. A series of interlocking gears are positioned above the base, with one gear having a small circular tag attached to it. On the right side, there is a vertical support structure with a handle and a small wheel. The entire assembly is labeled with various numbers: '7' on the top left, '46' and '50' at the top right, '44' and '43' on the right side, and '67' on the central lever.

UNITED STATES PATENT OFFICE

2,600,982

CONTROL AND CUTOFF MECHANISM FOR FILLING MACHINES

Paul R. Fechheimer, Cincinnati, Ohio, assignor
to The Karl Kiefer Machine Company, Cincinnati,
Ohio, a corporation of Ohio

Application July 3, 1946, Serial No. 681,291

15 Claims. (Cl. 226—97)

1 My invention relates to filling machines for jars, cans, bottles, collapsible tubes and the like, and it has for its principal object the provision of novel means for controlling the flow of the filling substance during the normal operation of the machine and for cutting off the flow of filling substance in the event of machine stoppage for any reason.

In order that the invention may be fully understood, I shall describe it in an exemplary embodiment applied to a known filling machine, the machine of Patent No. 2,184,117, it being understood that the invention may be applied to other types of devices. In that patent, to which reference is made for a fuller description of the filling machine, I have described a mechanism in which the containers are filled during continuous travel and in which more than one container may be filled simultaneously, thus greatly increasing the capacity of the machine. This is accomplished by successively connecting the filling spout for each container to different feed lines for or sources of the filling material for predetermined lengths of time, so that each container is filled by increments, the volume as well as the rate of flow of which can be accurately controlled so that each container will receive the same fill at a desired and controllable rate or rates. The machine also has various safety stop features which will be taken up hereinafter.

One of the objects of this invention is to provide in a combination such as that herein set forth, a flow-control and cut-off means very close to the filling spout, so that the flow of material can be more accurately started and stopped in the normal operation of the machine, and with less dripping and drainage than would be the case were reliance placed alone on the operation of ports in the filling head or valves at a distance from the spouts.

Another of the objects of the invention is to provide a mechanism whereby the flow of filling material may be cut off at the spouts immediately and positively if anything interferes with the normal operation of the machine, irrespective of the position of the ports at the time and irrespective of the operation of pumps or other flow control means located at a distance from the spouts.

These and other objects of the invention which will be set forth hereinafter or will be apparent to one skilled in the art upon reading these specifications, I accomplish by that construction and arrangement of parts of which I shall now describe the aforesaid exemplary embodiment. Reference is made to the accompanying drawings, wherein:

Figure 1 is a side elevation of the machine with certain parts cut away.

Figure 2 is a partial end elevation showing the

filling head and certain parts of my novel mechanism.

Figure 3 is a horizontal section of the exemplary machine taken along the line 3—3 of Figure 1.

Figure 4 is a plan view of the filling head.

Figure 5 is a semi-sectional view taken along the line 5—5 of Figure 4.

Figure 6 is a semi-sectional view taken along the line 6—6 of Figure 5.

Figure 7 is a partial elevational view of a valve and spout device.

Briefly in the practice of my invention, I provide adjacent each filling spout a positively acting valve resiliently biased to cut-off position. The valves are operated by cam means which is shaped and adjusted to give the required accuracy of valve operation, and which during the normal operation of the machine is stationary. Upon the occurrence of any interference with the normal operation of the machine the entire cam mechanism is moved in such fashion as to permit any valves which may be open to close instantly, all as will be more fully explained hereinafter.

The exemplary machine to which I have applied the present invention comprises a frame 1, upon which the various parts are mounted. The prime mover may be a motor 2, provided with an expandable or change speed pulley 4. The motor is slidably mounted on the machine base so that its position may be controlled by a hand wheel 7, with a resulting change of driving speed. A belt connects the pulley 4 with a pulley 8 on the main shaft 9 of the machine. The pulley 8 is connectible with the shaft through a clutch mechanism indicated generally at 10.

Within a housing 11, a worm on the shaft 9 engages a worm wheel on a vertical shaft 12, which extends upwardly through the top of the frame of the machine.

Referring to Figure 5, it will be seen that the shaft 12 carries a table 13 arranged to rotate with it. Above the table there is a star wheel or the like 14, also arranged to rotate with the shaft. The table has a plurality of platform members 15, located beneath the openings in the star wheel and mounted upon rods 16, journaled in the table so as to be vertically slideable. A fixed cam means 17 on the top 1a of the machine frame controls the positions of these platforms in such a way that at one machine station the platforms are lowered so that filled containers may be removed from the openings in the star wheel and empty containers placed in such openings, the containers passing freely beneath overhead pouring spouts. At other machine positions the cam 17 serves to raise the platforms as shown at the right in Figure 5, bringing the container mouths into

a proper relationship with the overhead filling spouts for the filling operation.

The shaft 12 is threaded as to its upper portion, and a lower head member 18 carrying filling spouts 19 is mounted thereon in such a way as to rotate with the shaft. For adjusting the mechanism for containers of different sizes, lower head 18 may be raised and lowered on the shaft 12 by means of a hand wheel 20, a threaded portion of which engages the threads of the 10 shaft.

An upper head member 21 is rotatively mounted with respect to the shaft, rests with a sliding and liquid-tight fit on the lower head 18, and is held from rotation during the rotation of the lower head by means of an arm 22, engaging a post on the machine. The upper head 21 has conduit connections 23 and 24 with two or more feed lines or sources of supply of the filling material. By a construction fully outlined in the said Patent No. 2,184,117, there are 15 cooperating ports in the heads 18 and 21, functioning in such fashion that the filling spouts 19 are successively connected for predetermined lengths of time with the several conduits 23, 24.

Referring to Figures 1 and 3, a small sprocket 25 and a larger sprocket 26 are rotatively mounted upon the main shaft 9. These are respectively connected by chains 27 and 28, to large and small sprockets 29 and 30 on a shaft 31. A clutch member 32 splined on the shaft 9, serves alternatively to connect either of the sprockets 25 or 26, with the shaft 9, or to disconnect both. The clutch member 32 is moved by a fork 33 pivoted on the machine frame as at 34, and provided with an operating handle 35. In this way I provide for driving the shaft 31 from the shaft 9, at two widely divergent speeds. A variable speed transmission 36 is connected to the shaft 31, and this combination enables me to control accurately over a very wide range, the speeds of the feeding mechanisms hereinafter described. The variable speed transmission 36 has a control shaft 37 carrying a sprocket 38, which is connected by a chain 39, to a sprocket 40. This sprocket is on a shaft journaled in the machine frame and bearing a hand wheel 41. The wide range of speed control heretofore mentioned is effected by manipulation of the hand wheel 41, and the operating lever 35, these being located close together.

The driven shaft of the change speed transmission 36 has a sprocket 42 connected by a chain 43 to a sprocket 44 on a shaft 45 at the side of the machine. The shaft 45 may be on, or may be connected to, the operating shaft of a pump 46. I have shown a second pump 47, the shaft of which carries a sprocket 48 connected by a chain 49 to another sprocket 50, on the shaft 45. The two pumps 46 and 47, each of which is capable of delivering the filling material at a volumetric rate proportional to the speed of its shaft, are connected together and driven together from the driven shaft of the change speed mechanism 36. The volumetric performance of each pump relative to the performance of the other, will be determined by the connection between the two pumps, which connection may be chosen or modified to bring about the required relative performance. The combined volumetric performance of both pumps will be determined by the change speed mechanism 36, and thus may be adjusted for con-

tainers of different sizes, the proportionate performance of the pumps remaining the same.

Pump 47 is shown as having a valved inlet means 51, while pump 46 has a valved inlet means 52. The outlet port of pump 46 is shown as connected to the head conduit 24 by a conduit 24a including sliding means so that the head mechanism heretofore described can be raised and lowered. Similarly the outlet port of pump 47 is connected to the head inlet means 23 by a conduit 23a having sliding means. My containers may be filled with successive increments of different substances by the means described; and with suitable modification of the construction of the head, the number of increments introduced into each container may be increased by multiplying pumps, drives and conduits. It will be understood that the containers may also be filled with successive increments of the same filling material from different sources; and a valved cross connection 53 between the inlet sides of the pumps enables me to fill containers with successive increments of the same filling material from the same source.

The clutch member 10, splined on the main shaft 9 is operated by a fork control lever 54 pivoted as at 55 on the machine. A heavy tension spring 56 connected between the end of the lever 54 and an abutment 57 on the machine, tends to urge the lever to a position in which the clutch 10 is open. It will be noted that the clutch 10 is a main clutch serving to disconnect the prime mover both from the shaft 12 of the machine table and from the pumps through the variable speed transmission 36.

The lever 54 is connected by a link or rod 58 to a bell crank 59 pivoted on the machine and having an operating handle 60. A member 61 fixed on the rod 58 carries a detent, and a co-operating detent is found on a latch means 62 pivoted to the machine frame at 63, and controlled by a compression spring 64. Thus the clutch member 10 may be thrown into engaged position by the handle 60, and will be held in that position by the latch means just described.

For disengaging the latch and hence permitting the spring 56 to throw out the clutch, I have shown a solenoid 65, the armature 66 of which is connected with the latch member 62. Energization of the solenoid will cause a movement of the latch against the spring 64, disengaging the detents.

The machine of Patent No. 2,184,117 was provided with certain safety features, operating to energize the solenoid 61. The worm wheel in the housing 11 was not affixed directly to the shaft 12, but was rotatively mounted thereon and was provided with a connection means or clutch sufficient to transmit power under ordinary requirements, but arranged to throw itself out under conditions of extraordinary power requirements, as when a jam occurs in the machine. In throwing itself out, the clutch operated a lever (67 in Figure 1) which, by means of a transmission indicated at 68, which does not need to be described in detail, operated a mercury switch 69 (Fig. 3).

The containers approach the table 13 and star wheel 14 on a conveyor 70 (Figure 1). Means 70 are provided to deflect the approaching containers into the star wheel, and for removing them from the star wheel to the conveyor, whereupon they are carried away in a continuation of the original direction. At 71 I provide means 75 of a character to be moved if a container ap-

proaches the star wheel incorrectly or fails to seat properly in an opening of the star wheel, together with means which will move if a star wheel opening fails to receive a container. These means through a transmission indicated generally at 72 in Figure 3, operate another mercury switch 74. Again, the several mechanisms do not require detailed description especially since they are fully described in Patent No. 2,184,117.

The mercury switches 69 and 74 are connected in the circuit of the solenoid 65 so that either switch can produce energization of the solenoid. Additional safety mechanisms may be added to the machine and arranged to produce energization of the solenoid 65 upon the occurrence of undesired conditions during machine operation. Also a special, manually operated, quick-stop button may be provided for the machine and connected into the same circuit. The new mechanism which I shall next describe, is arranged to be operated automatically upon the occurrence of any stoppage of the machine, whether produced manually or by the operation of any type of safety mechanism.

Referring to Figures 4, 5 and 7, in my machine, I connect each filling spout 19 to the rotating lower head 18 (and to an outlet port therein) by means of a hollow neck or connecting member 75. Within this neck I provide a positive cut-off valve of any suitable type. The particular exemplary valve is a rotating valve of the perforated barrel type. A member 76 on or connected with the rotating barrel extends through a side arm on the neck 75, and is provided with a crank arm 77 for rotating the barrel. The outer end of this crank arm carries a cam following roller 78. A spring 79 is wound around the side arm, having one end connected to the side arm and the other end connected to a part of the crank 77. The action of the spring is to urge the crank arm from the valve open position shown in solid lines in Figure 7, to a valve closed position shown in dotted lines in the same figure. Thus, unless definitely actuated, the various valves in connection with the various filling spouts will remain closed.

While in the drawings I have shown filling spouts depending from the valved connecting members, it will be understood that the valves may be located very close to or actually at the tips of the spout means, which is desirable in filling certain materials.

A cam is provided to actuate the valves to open position, mounted on the mechanism next to be described. A central post 80 and two side posts 81 and 82 (Figure 6), are slidably journaled in a cover member 83 spaced from the top plate 1a of the machine frame. The two outer posts 81 and 82, extend through and are also journaled in the top plate 1a. A bridge or bar 84 connects the three posts below the cover plate 83. Between this bridge and the top plate 1a of the machine frame, I provide a toggle connection comprising links or sets of links 85 and 86. The links 85 are pivoted to the bridge and to the links 86 while the latter are pivoted to a bracket 87, on the top plate of the machine. The cam member 88 is mounted on the upper ends of the posts. It is provided with clamping means 89 and 90 by which it may be affixed in adjusted position on the posts 81 and 82; but when the clamps are loosened, it is slideable with respect to these posts. The central post 80 is threaded as shown and a hand wheel 91 is provided whereby

the height of the cam may be adjusted with respect to the position of the head 18.

The pivoting of the link or links 85 to the bracket 87 is accomplished by means of a shaft 92, which is affixed to the links. The shaft extends through the cover member of the machine and is provided with a rigidly attached arm 93, carrying a weight 94, or is otherwise biased to offset the load of the spout valve springs and the weight of the cam and its mounting. The links 85 and 86 are designed to rest slightly past dead center against any suitable stop (not shown) as indicated in Figure 6, where they maintain the cam in its highest position. This is the position for normal operation of the machine and is also the position at which the cam 88 is adjusted to open the valves. A consideration of Figure 4 will indicate that the cam 88 is so positioned as to open and close the valves at the filling spouts at the proper times during the travel of containers in the machine. Thus the flow of material to the containers is accurately started and accurately stopped, and dripping is minimized.

Without interfering with the normal operation of the machine, I provide means whereby the cam may be bodily lowered to bring all valves to the closed position when the machine stops as aforesaid. This is accomplished through a lowering of the posts 80, 81 and 82, by means exerting a definite displacement of the intermediate pivot of the toggle arrangement 85, 86, to lower the bridge 84. I engage a link or rod 95 with the intermediate pivot of the toggle, and connect the opposite end of it to a crank arm 96 (Figure 3), on a stub shaft 97 journaled on the machine frame. This shaft carries another lever 98, which is connected with the clutch operating lever 54, by means of a link 99.

In the particular embodiment described, if anything occurs to energize the solenoid 65, opening the latch 62 and permitting the spring 56 to throw the clutch lever 54 so as to open the clutch 10, the rod 95 will be actuated to cause the toggle 85, 86, to lower the posts 80, 81 and 82. This carries the cam 88 down far enough so that the previously actuated valves adjacent the filling spouts of my device will close through the action of the springs 79. Thus I obtain automatically a complete stoppage of the flow of filling material through all filling spouts upon stoppage of the machine for any cause whatever, including both manual operation and the operation of any safety devices which may be provided. The cessation of the flow of filling material through the filling spouts occurs irrespective of any over-running of parts due to their momentum, irrespective of any continued operation of the pumps, and irrespective of the relative positions of the ports in the heads 18 and 21.

My invention also makes for accuracy of fill in the following way. When a filling machine is in operation, pressure is built up in the lines between the pumps and the head. When the machine is stopped, the filling material tends to relieve this pressure by continuing to flow into any containers located under spouts connected to ports which are open for filling. Such containers will be over filled and may even overflow. Furthermore, when the machine is again started, the containers immediately succeeding the over-filled containers will be under-filled. My invention operates to prevent the relief of pressure in this fashion, by closing off the lines immediately adjacent the filling spout as has been described.

Modifications may be made in my invention without departing from the spirit of it. While I have described my invention in an exemplary embodiment, applied to an exemplary known machine, it will be evident from the teachings above, that it may be applied to other types of machines and to other environments to the same effect. Hence what I claim as new, and desire to secure by Letters Patent is:

1. In a filling machine for containers, a filling spout, means to supply filling material to the filling spout, a valve adjacent said filling spout, cam means for actuating said valve to open it at the start of a filling operation and to close it at the conclusion thereof, means for supporting said cam stationarily in valve operating position during normal operation of the machine and means for bodily moving said cam to an inoperative position upon interruption of the filling operation.

2. In a filling machine for containers, a plurality of filling spouts, means to supply filling material to the filling spouts, a valve adjacent each of said filling spouts, cam means acting automatically to open said valve sequentially at the start of a filling operation and to close them sequentially at the conclusion thereof, and means for supporting said cam means stationarily in valve operating position during normal operation of the machine, and means for bodily moving said cam means to an inoperative position upon interruption of the filling operation.

3. In a filling machine for containers, a filling spout, means for supplying material to said filling spout, means for moving said containers in a path of travel means for causing said filling spout to travel with a travelling container, a valve adjacent said filling spout and arranged to be actuated by a cam, a cam for actuating said valve to open it at the start of a filling operation and close it at the conclusion thereof, means for supporting said cam stationarily in valve operating position during normal operation of the machine, and means for bodily moving said cam to an inoperative position upon occurrence of stoppage of said machine.

4. In a filling machine for containers, a filling spout, means for supplying material to said filling spout, means for moving said containers in a path of travel means for causing said filling spout to travel with a travelling container, a valve adjacent said filling spout and arranged to be actuated by a cam, a cam for actuating said valve to open it at the start of a filling operation and close it at the conclusion thereof, means for supporting said cam stationarily in valve operating position during normal operation of the machine, and means for bodily moving said cam to an inoperative position upon occurrence of stoppage of said machine, said last mentioned means comprising at least one vertical rod, means for supporting said rod in a fixed vertical position, and means for moving said rod downwardly upon the occurrence of stoppage in the machine.

5. In a machine for filling containers, a rotating head carrying filling spouts, means for moving containers in conjunction with said head so that a filling spout is positioned with respect to each container to introduce filling material therein, valves adjacent said filling spouts having operating means extending beyond said head, means biasing said operating means to valve

closing position, a cam for moving said valve operating means against said biasing means, means for supporting said cam fixedly during normal operations of said machine, and means for moving said cam to an inoperative position to allow said biasing means to close said valves.

6. In a machine for filling containers, means for moving containers, a movable head having filling spouts, means for moving said head so as to move said spouts with respective containers, means for supplying filling material to said spouts, valves adjacent said spouts and having operating means biased to valve closing position, a cam for operating said valves during a portion of the travel of said containers, means for supporting said cam in a fixed operative position, and means for bodily moving said cam to an inoperative position to cause said valves to close.

20 7. In a machine for filling containers, means for moving containers, a movable head having filling spouts, means for moving said head so as to move said spouts with respective containers, means for supplying filling material to said spouts, valves adjacent said spouts and having operating means biased to valve closing position, a cam for operating said valves during a portion of the travel of said containers, means for supporting said cam in a fixed operative position, means for bodily moving said cam to an inoperative position to cause said valves to close, and actuating means for said last mentioned means energized upon the occurrence of a stoppage in the machine.

25 8. In a filling machine for containers, a table upon which containers may be moved through a path of travel, locating means for containers to position them on said table, a rotating head having filling spouts, means to move said head with said table whereby to cause said filling spouts to travel with containers, a fixed head cooperating with the movable head, means in connection with said fixed head to supply filling material thereto, cooperating ports in said fixed head and said movable head to supply filling material to said spouts at given portions of their paths of travel, valves adjacent said filling spouts, a cam for operating said valves in synchronism with the opening and closing of said ports, and means for closing said valves irrespective of the operation of said ports, said last mentioned means comprising means for bodily moving said cam to an operative position.

30 9. In a filling machine for containers, a rotating table, means for locating containers on said table, a head rotating with said table, filling spouts on said head movable with containers on said table, means for supplying filling material to said filling spouts, valves adjacent said filling spouts, means for operating said valves to open and close them at the start and end of filling operations on respective containers, and means for closing said valves upon stoppage of said machine, said means for operating said valves comprising a cam, and means for holding said cam in a fixed operative position during normal operation of said machine, said means for closing said valves upon stoppage of the machine comprising means for bodily moving said cam.

35 10. In a filling machine for containers a rotative table, means for locating containers in said table, a rotative filling head, filling spouts on said head, means for rotating said head with said table so as to cause filling spouts to travel

with respective containers, a fixed head, means for supplying filling material to said fixed head, cooperating ports in said fixed and movable heads serving to connect said filling spouts with said supply means and disconnect them therefrom, valves adjacent said filling spouts, vertically slideable rods, a cam means supported by said rods for operating said valves in synchronism with the operation of said ports, and means for sliding said rods vertically so as to move said cam for closing said valves irrespective of the operation of said ports.

11. In a filling machine for containers a rotative table, means for locating containers on said table, a rotative filling head, filling spouts on said head, means for rotating said head with said table so as to cause filling spouts to travel with respective containers, a fixed head, means for supplying filling material to said fixed head, cooperating ports in said fixed and movable heads serving to connect said filling spouts with said supply means and disconnect them therefrom, valves adjacent said filling spouts, vertically slideable rods, a cam means supported by said rods for operating said valves in synchronism with the operation of said ports, and means for sliding said rods vertically so as to move said cam for closing said valves irrespective of the operation of said ports, said machine having a drive and a clutch, means for throwing out said clutch upon the occurrence of a jam in said machine, and a connection between said throw-out means and said means for moving said cam.

12. In a filling machine for containers, a rotative table, means for locating containers on said table, a rotative filling head, filling spouts on said head, means for rotating said head with said table so as to cause filling spouts to travel with respective containers, a fixed head, means for supplying filling material to said fixed head, cooperating ports in said fixed and movable heads serving to connect said filling spouts with said supply means and disconnect them therefrom, valves adjacent said filling spouts, vertically slideable rods, a cam means supported by said rods for operating said valves in synchronism with the operation of said ports, and means for sliding said rods vertically so as to move said cam for closing said valves irrespective of the operation of said ports, said machine having a drive and a clutch, means for throwing out said clutch upon the occurrence of a jam in said machine, and a connection between said throw-out means and said means for moving said cam, said fixed head having connections with a plurality of feeding means for filling material, said feeding means including individual pumps, the action of said ports in said fixed and movable heads being such as to connect said filling spouts successively with said several feeding means, drive means interconnecting said pumps in a given ratio, and drive means connecting the interconnected pumps with said machine drive means so as to be affected by said clutch.

13. In a filling machine for containers a rotative table, means for locating containers on said table, a rotative filling head, filling spouts on said head, means for rotating said head with said table so as to cause filling spouts to travel with respective containers, a fixed head, means for supplying filling material to said fixed head, cooperating ports in said fixed and movable heads serving to connect said filling spouts with

said supply means and disconnect them therefrom, valves adjacent said filling spouts, vertically slideable rods, a cam means supported by said rods for operating said valves in synchronism with the operation of said ports, and means for sliding said rods vertically so as to move said cam for closing said valves irrespective of the operation of said ports, said machine having a drive and a clutch, means for throwing out said clutch upon the occurrence of a jam in said machine, and a connection between said throw-out means and said means for moving said cam, said fixed head having connections with a plurality of feeding means for filling material, said feeding means including individual pumps, the action of said ports in said fixed and movable heads being such as to connect said filling spouts successively with said several feeding means, drive means interconnecting said pumps in a given ratio, and drive means connecting the interconnected pumps with said machine drive means so as to be affected by said clutch, and further means for throwing out said clutch upon the occurrence of a misplacement of containers whereby also to actuate said cam.

14. In a device of the character described a filling head having valved filling spouts, resilient means biasing the operating elements of the valves to cut off position, a cam means for engaging and operating the operating elements of the valves, a movable support for said cam means comprising at least one vertically slideable rod, toggle means connecting said rod with a support, resiliently acting means in connection with the toggle means for counteracting the weight of the cam and its support and the load of the resilient valve biasing means, and means in connection with said toggle means for moving said cam to an inoperative position as respects all of said valves.

15. In a filling machine for containers, means for moving containers in a path, a movable head having filling spouts, means for moving said head to cause said filling spouts to travel with respective ones of said containers, a fixed head cooperating with the movable head, means for supplying filling material to said fixed head through different feeding means, cooperating ports in said fixed head and said movable head operating to connect said filling spouts in sequence with different ones of said feeding means and to interrupt the flow of the filling material, valves adjacent said filling spouts, cam means operating said valves in synchronism with the operation of said ports, and means for holding said cam means in a fixed operative position during normal operation of said machine, and means for bodily moving said cam to an inoperative position upon interruption of the filling operation.
